(57) CLAIM

I claim the ornamental design for a foot splint, substantially as shown.

DESCRIPTION

FIG. 1 is a perspective view of a foot splint, showing my new design;

FIG. 2 is a side elevational view thereof, on an enlarged scale;

FIG. 3 is a rear elevational view thereof;

FIG. 4 is a front elevational view thereof;

FIG. 5 is a top plan view thereof; and,

FIG. 6 is a bottom plan view thereof.
